UNITED STATES PATENT OFFICE.

JENNY BRAASCH FORTAIN, OF REDONDO BEACH, CALIFORNIA.

WATER AND SOAP SAVING DEVICE.

Application filed October 29, 1927. Serial No. 229,726.

In the operation of plumbing systems, there is a great deal of soapy and other water discharged from kitchen sinks, wash-stands, bath tubs, laundry tubs, washing machines, etc., into the usual stack or other pipe leading to the sewer. This water is fit for further use, such as for irrigation and hence it is advantageous, particularly in localities having a scarcity of water, to con-5 serve that which is now wasted. It is the object of my invention to provide a novel means for attaining this end.

The invention is illustrated in the accompanying drawing forming a part of this 15 application.

Fig. 1 of the drawing is a side elevation partly broken away and in section, showing my invention in connection with a kitchen sink.

20 Fig. 2 is a view similar to Fig. 1 but illustrating the invention in connection with a sink and a bath tub above said sink.

Fig. 3 is a view similar to Figs. 1 and 2 but showing the invention in connection with 25 a washing machine and a laundry tub.

In Figs. 1 and 2, the numeral 4 denotes a kitchen sink, 5 has reference to the usual stack or other pipe leading to the sewer, and 6 denotes the waste pipe from sink to stack, 30 said waste pipe embodying the usual trap 7.

Below the sink 4, preferably in the basement, is a closed water-collecting tank 8. Leading to this tank from the trap 7, is a water-conducting pipe 9 having a cutoff 35 valve 10. This pipe 9 communicates with the trap 7 at a point 11 between the lowest point of the trap and the outlet end 12 of said trap. Hence, trap 7 seals both the pipe 9 and the waste pipe 6 against escape 40 of gas, and with the valve 10 open, all water from the sink or the like 4 will descend from the trap 7 through the pipe 9 and into the tank 8, instead of flowing to a level above the point 11 and discharging on through the waste pipe 6 to the stack or the like 5. How-45 ever, as soon as the tank 8 and the pipe 9 are entirely filled, the water from the sink or the like 4 will travel on through the waste pipe 6 and into the stack or other pipe 5.

50 Whenever it is desired that water shall not enter the tank 8, the valve 10 may be closed.

Any desired provision may be made for removing the accumulated water from the tank 8. For this purpose, I have shown it 55 provided with a spigot 13 at its lower end. The water from this spigot may be received

in an appropriate container (not shown) or a hose 14 may be connected with said spigot. When it is desired that the tank 8 shall receive waste water from a bath tub 15, the 60 waste pipe 16 from said tub may be connected with the pipe 9 as shown in Fig. 2. When this installation is used, waste water from the tub 15 and the sink or the like 4 will discharge into the tank 8 until the pipe 65 9 has been entirely filled after complete filling of the tank 8. Then, the waste water will travel on through the waste pipe 6 of the sink 4, to the stack 5.

In Fig. 3, a washing machine 17 and a 70 laundry tub 18 have been shown, having waste pipes provided with traps 19-20, said waste pipes leading to the stack 21. Piping 22 equipped with valves 23, leads from the waste pipes to a water-collecting tank 24, 75 the upper ends of this piping being connected with the traps 19-20 below their outlets, so that waste water will discharge through said piping into the tank 24 until piping and tank are full, and will thereafter 80 travel on to the stack 21. A spigot 25 is shown on the tank 24 for draining water therefrom within the basement or the like, and a discharge pipe 26 is shown leading from said tank to the exterior of the building, permitting the water to be drawn out 85 from the tank and used, for irrigating or other desired purposes.

I claim:

1. In combination with a plumbing fixture, a stack, and a waste pipe from fixture to stack embodying a trap; a closed water-collecting tank below said trap, and piping leading from said trap to said tank, said piping communicating with the trap at a point between said fixture and the outlet end of said trap, whereby water from the fixture will descend through said piping until the tank and piping are full and will thereafter travel on through the waste pipe 100 to the stack.

2. In combination with a plumbing fixture, a stack, and a waste pipe from fixture to stack embodying a trap; a closed water-collecting tank below said trap, and piping leading from said trap to said tank, said piping communicating with the trap at a point between the lowest point of said trap and the outlet end of said trap, whereby water from the fixture will descend through 105 said piping until the tank and piping are full and will thereafter travel on through

the waste pipe to the stack, and whereby said trap will seal both said waste pipe and said piping against escape of gases.

3. In combination with a plumbing fixture, a stack, and a waste pipe from fixture to stack embodying a trap; a closed water-collecting tank below said trap, a water-conducting pipe leading from said trap to said tank, an additional plumbing fixture above the first named fixture, and an additional water-conducting pipe from said additional fixture to the first named water-

conducting pipe, said first named water-conducting pipe communicating with said trap at a point between the first named fixture and the outlet of said trap, whereby water from both fixtures will descend to said tank until the latter and both of said water-conducting pipes are full and will thereafter travel on to said stack. 15

20 In testimony whereof I have hereunto affixed my signature.

JENNY BRAASCH FORTAIN.
